No. 36,371.

Patented June 16, 1903.

UNITED STATES PATENT OFFICE.

CHARLES GANTERT, OF ROCK ISLAND, ILLINOIS.

DESIGN FOR A SHOW-CASE.

SPECIFICATION forming part of Design No. 36,371, dated June 16, 1903.

Application filed May 15, 1903. Serial No. 157,326. Term of patent 7 years.

To all whom it may concern:

Be it known that I, CHARLES GANTERT, a citizen of the United States, residing in the city of Rock Island, county of Rock Island, 5 and State of Illinois, have invented a new and original Design for Show-Cases, of which the following is a specification, reference being had to the accompanying drawing, forming part thereof.

10 My said design is for the show-case shown

in the accompanying drawing, which represents a perspective view thereof.

I claim—

The ornamental design for show-case, as shown.

CHARLES GANTERT.
